UNITED STATES PATENT OFFICE.

JOHN POSTOLOWSKI, OF NEW YORK, N. Y.

CIGARETTE-CASE.

1,252,944.

Specification of Letters Patent.

Patented Jan. 8, 1918.

Application filed February 12, 1917. Serial No. 148,147.

To all whom it may concern:

Be it known that I, JOHN POSTOLOWSKI, a subject of the Czar of Russia, residing at New York, in the county of New York and State of New York, have invented certain new and useful Improvements in Cigarette-Cases, of which the following is a specification.

This invention relates to cigarette boxes or cases and has special reference to a combined match and cigarette box.

One important object of the invention is to provide an improved and simplified general construction of devices of this character.

15 A second important object of the invention is to provide a compartment match and cigarette box having a sliding drawer extending out through one side thereof and a hinged top, the top being provided with a 20 depending flange and the drawer with an end forming a flange about the drawer, the drawer end resting against the front of the box when the drawer is closed and the depending flange being cutaway or notched to

25 engage about the drawer end so that the drawer end will not be caught in the clothing when placing a box in the pocket or the like while at the same time there will be no bulge on the front side of the box.

30 With the above and other objects in view, as will be hereinafter apparent the invention consists in general of certain novel details of construction and combination of parts hereinafter fully described, illustrated in 35 the accompanying drawings, and specifically claimed.

In the accompanying drawing, like characters of reference indicate like parts in the several views, and:-

40 Figure 1 is a perspective view of one form of the box in its open position.

Fig. 2 is a similar view of such a form closed.

Fig. 3 is a perspective view of a portion of 45 the bottom of the box showing the means for holding an abrasive strip.

Fig. 4 is a longitudinal section through the box.

Fig. 5 is a transverse section through said 50 box.

In the construction of this box there is provided a bottom 10 having side walls 11, a front wall 12 and a back wall 13. In both forms of the box there is provided a top 14 55 having a peripheral flange 15, the flange at the back of the top being hinged by a strip

16 to the bottom of the box as is frequently the case with ordinary cigarette boxes. Furthermore, in order to divide the box into cigarette and match compartments there is provided a strip of material the width of which is equal to the interior width of the box between the flanges 12 and 13 while its length is greater than the distance between the flanges 11 measured interiorly of said flanges or sides. This strip is rectangularly bent centrally so that there are formed bottom portions 17, spaced upstanding portions 18 and a top connecting portion 19 which is spaced from the bottom 10 of the box or body proper. Moreover, it is preferred that these upstanding portions 18 be of the same width as the walls 11, 12 and 13 so that by this means there is formed a central match receiving compartment M and lateral cigarette receiving compartments C. Moreover, it will be noted that by reason of the height of the portions 18 the cigarette compartments are completely closed off from each other when the top is closed.

As shown in Figs. 1 to 5 the front wall 12 is provided with an opening 20 wherein is slidably mounted a drawer 21. This drawer 21 has a front 22 which extends preferably about the body of the drawer so that when the drawer is closed the front forms a flange which butts against the front wall 12. Similarly the front portion of the flange 15 of the top is cutaway in this form as indicated at 23 and this cutaway portion 23 is of such size as to neatly fit about the end 22 as shown in Fig. 2. Furthermore, it is preferable that this end 22 and the flange 15 be of the same thickness so that when the box is closed as in Fig. 2 the front is substantially a flush surface. This drawer 21 is provided with a pull tab 29.

Adjacent one side of the box the bottom is provided with a recess, 30 and at the end this recess extends beneath overhanging portions 31 of the bottom so that an abrasive strip 32 may be inserted in the recess and have its ends tucked beneath the overhanging portions 31 to hold it in position. Now, in this position it would be difficult to remove the abrasive strip for replacement after it is worn out but in order to facilitate this removal a slot 33 is formed which extends from the recess outward to the adjacent side of the box so that a knife-blade or toothpick may be slipped into this slot 33 beneath the strip 32 thus enabling the strip to be

raised out of the recess and its ends withdrawn from beneath the overhanging portions 31 so that a new strip may be placed in position.

- 5 In use it will be obvious that the compartments C are intended to contain the cigarettes while the compartment M contains the matches and, by reason of the fact that these compartments have independent 10 closures, the cigarette compartments may be opened and a cigarette withdrawn. This closure can then be closed to keep the remaining cigarettes in the box and the match compartment opened for the withdrawal of 15 a match.

There has thus been provided a simple and efficient device of the kind described and for the purpose specified.

It is obvious that many minor changes 20 may be made in the form and construction of the invention without departing from the material principles thereof. It is not therefore desired to confine the invention to the exact form herein shown and described but 25 it is wished to include all such as properly come within the scope claimed.

Having thus described the invention, what is claimed as new is:—

In a box of the class described, a rectangular body portion divided into a central compartment and a plurality of lateral compartments, said central compartment extending from front to back of the box, the front wall of the box having an opening therein communicating with the central compartment, a drawer slideable into and out of the central compartment through said opening, an end on said drawer of greater dimensions than the cross section of the drawer and arranged to form a peripheral 35 flange, said flange normally lying against the outer surface of the front wall of the box, and a top hinged to the back wall of the box and provided with a depending flange embracing the walls of the box body, 40 the front portion of the top flange being cutaway to fit around the drawer end.

In testimony whereof I affix my signature,

JOHN POSTOLOWSKI.

In the presence of—

MARY K. FLAHERTY,
MAX LEVINEP.
